FACIAL MASSAGE IRON

Elizabeth Krause, St. Louis, Mo.

Application February 12, 1949, Serial No. 825

Term of patent 7 years

(Cl. D83—1)

To all whom it may concern:

Be it known that I, Elizabeth Krause, a citizen of the United States, residing at 3865 Delmar Avenue, St. Louis, in the county of St. Louis and State of Missouri, have invented a new, original, and ornamental Design for a Facial Massage Iron, of which the following is a specification, reference being had to the accompanying drawing, forming part thereof.

In the drawing

Fig. 1 is a side elevational view of a facial massage iron showing my new design;

Fig. 2 is a front end elevational view, looking towards the right hand end of Figure 1.

Fig. 3 is a top plan view.

Fig. 4 is a rear end elevational view, looking towards the left hand end of Figure 1.

I claim:

The ornamental design for a facial massage iron, as shown.

ELIZABETH KRAUSE.
